UNITED STATES PATENT OFFICE.

JOHN A. NEILL, OF SHERIDAN, INDIANA.

LANTERN.

1,082,896.

Specification of Letters Patent.

Patented Dec. 30, 1913.

Application filed October 23, 1912. Serial No. 727,393.

To all whom it may concern:

Be it known that I, JOHN A. NEILL, a citizen of the United States, residing at Sheridan, in the county of Hamilton, State 5 of Indiana, have invented certain new and useful Improvements in Lanterns; and I do hereby declare the following to be a full, clear, and exact description of the invention, such as will enable others skilled in the art to 10 which it appertains to make and use the same.

This invention relates to lanterns, and has for one of its objects to provide a lantern which is adapted to be secured to the person 15 of the user, so that the light will always shine in front of the person.

Another object is to provide a lantern adapted to be secured to the person of the user, and obviates the necessity of finding 20 some place to hang or set the lantern. The ordinary hand lantern, that is the lantern using oil, has to be carried about in the hand, and when the user desires to perform some work he finds it necessary to dispose 25 of the lantern in some way, either by finding a suitable place to hang the lantern or a level place to set the same, so that it will be near at hand to furnish its light in the proper direction. This is often found very 30 inconvenient, as the place where the lamp might be hung is too far away for the person to benefit by its light, or there is no level place in the vicinity of the work being performed, on which to rest the lantern. Now, 35 by my invention, the lantern is always with the person and sheds its light directly in front of him, so that he may readily see what he is doing.

Another object is to construct the lantern 40 at the portion against the body, so that the heat from the lantern will be dissipated and a comparatively cool surface be presented next the body.

A still further object is to provide a lantern, which may readily be attached to, and detached from its support.

With these and other objects in view, the invention consists in the construction, combination and arrangement of parts, as will 50 be more fully hereinafter described and pointed out in the claims, but it will be understood that changes in the specific structure may be made within the scope of the claims, without departing from the 55 spirit of the invention.

In the drawings, Figure 1, is a perspec-

tive view of the device, Fig. 2, is a front elevation of the lantern, and attaching means, Fig. 3, is a side elevation thereof, Fig. 4, is a top plan view, Fig. 5, is a section on the line 5—5 of Fig. 2, Fig. 6, is a section on the line 6—6 of Fig. 4, Fig. 7, is a section on the line 7—7 of Fig. 6, and Fig. 8, is a section on the line 8—8 of Fig. 6, Fig. 9 is a plan view showing a modified form of support for 65 the lantern.

Referring to the drawings, 10 represents the top of the lantern proper and 11 the bottom, said top comprising a hollow chamber having the upper wall 10' and the lower 70 wall 11', and also the side wall 12. The walls 11' and 12 are each formed with a series of perforations to allow the escape of smoke from within the lamp, the top wall 10 being imperforate. The top wall of the 75 bottom 11, has its free edges crimped to provide a groove 13 for the reception of the transparent plate 14, which may be of either glass or mica. Connecting the top and bottom of the lantern, are the side strips 15. 80 The bottom 11 is provided with a series of air inlet openings 16 to produce the proper combustion within the lantern.

Secured within the lantern and to the bottom is a candle holder 17, comprising a plate 85 18 whose lateral edges are doubled on themselves and toward each other to provide the grooves 19 for the reception of the laterally extending flanges 21 of the candle-stick 20. The candle-stick comprises a tubular socket 90 to receive a candle as shown, and said candle-stick is adapted to be inserted from the front of the lantern having its flanges 21 engaging in the groove 19 and pushed toward the back of the lantern, and is thus securely held in place.

The door of the lantern 22 is adapted to swing open from the front by the hinges 23, and is provided on the opposite side with the latch 24. The back 25 of the lantern is 100 provided with the flanges 26 tapering from top to bottom of the frame as shown in Fig. 2 and adapted to be seated in a correspondingly tapered socket 27 of the support 28. The support 28 comprises a rectangular 105 elongated hollow member having the front and rear walls 29 and the side walls 30, the walls 29 being disposed respectively against the lamp and toward the body of the wearer, while the walls 30 are exposed to the sides 110 of the rear of the lantern and are formed with a series of perforations 31 which per-

2
forations together with the opening 32 extending clear through the member 28 to permit of a circulation of air between the lantern and the person. The member 28 may 5 be convex as shown in Fig. 9, so as to fit the curvature of the body. Secured to the rear of the body 28, are the attaching straps 33 and 34 adapted to be passed respectively around the shoulders and the waist to secure 10 the lantern in place.

It will thus be seen, that when the lantern is in place the light is shed where it is best needed, and as there is a candle used in the same, the person may stoop over without 15 fear of danger, as will be the case with a lantern using oil.

From the foregoing it will readily be seen that I have provided a simple device of this character which is easily carried about, and 20 which can readily be taken apart to repair or clean same.

What is claimed is:

1. A lantern comprising a support adapted to be secured to the body of a person, 25 said support consisting of a vertical hollow

open ended member, attaching straps secured to the rear face of said member, socket members secured to the front face, a lamp having flanged members on the rear thereof for engagement in said socket member, the 30 hollow support having openings in the sides to permit a circulation of air therethrough.

2. A lantern comprising a support, attaching straps secured to the support on one side thereof, tapering socket members secured to the opposite side of said support, said support consisting of a hollow open-ended convex member, having openings in its side walls to permit circulation of air therethrough, a lamp consisting of a frame 40 having tapered flanges on the rear thereof, adapted to engage in the socket members, and means for holding a candle in said frame.

In testimony whereof I affix my signature, 45 in the presence of two witnesses.

JOHN A. NEILL.
